UNITED STATES PATENT OFFICE.

GEORGE HERMAN HORN, OF VESPER, WISCONSIN.

SILO.

1,031,794.

Specification of Letters Patent.

Patented July 9, 1912.

Application filed April 19, 1912. Serial No. 691,905.

To all whom it may concern:

Be it known that I, GEORGE H. HORN, a citizen of the United States, residing at Vesper, in the county of Wood and State of Wisconsin, have invented a new and useful Silo, of which the following is a specification.

The invention relates to improvements in silos.

10 The object of the present invention is to improve the construction of silos, more especially the means for adjustably connecting the hoops or binding rods, and to provide a simple, inexpensive and efficient adjusting device, adapted to form a permanent door opening without employing a door frame or brace, and capable of exerting an even pressure on the staves at each side of the door opening and of producing a uniform tension on the binding rods or hoops, and of enabling the same to be tightened without the use of a wrench, or other special tool.

With these and other objects in view, the invention consists in the construction and novel combination of parts hereinafter fully described, illustrated in the accompanying drawing, and pointed out in the claims here-to appended; it being understood that various changes in the form, proportion, size and minor details of construction, within the scope of the claims, may be resorted to without departing from the spirit or sacrificing any of the advantages of the invention.

In the drawing: Figure 1 is an elevation of a portion of a silo, showing one of the binding rods or hoops and an adjusting device, constructed in accordance with this invention. Fig. 2 is a horizontal sectional view of the same. Fig. 3 is a detail perspective view of one of the plates.

Like numerals of reference designate corresponding parts in all the figures of the drawing.

In the accompanying drawing in which is illustrated the preferred embodiment of the invention, the adjustable connection comprises in its construction a pair of approximately L-shaped plates 1, secured to the staves 2 of a silo at opposite sides of a door opening 3, and receiving the terminal portions of a hoop or binding rod 4. The L-shaped plate or member consists of an outer attaching wing or portion 5 and an inwardly extending transversely disposed en-

gaging flange 6, which fits against the edge of the stave 2 at the door opening 3. The outer attaching plate or portion 5, which is provided at opposite sides with perforations 7 for the reception of screws 8, or other suitable fastening devices for securing the plate to the stave 2, has a longitudinal opening 9 extending through a horizontally rounded enlargement 10, and receiving the terminal portions of the hoop 4. The outer attaching portion of the plate is preferably reinforced at the ends of the enlargement by ribs or bosses 11, and the inwardly extending stave engaging flange or portion 6, which is imperforate, is tapered and extends from the outer face of the stave 2 to the inner face thereof.

The terminal portions of the binding rod or hoop 4 extend through the openings 9, which are horizontally aligned, and the said terminal portions project beyond the plates 1 and extend partially across the door opening 3, being spaced apart at the central portion thereof. The ends 12 of the binding rod or hoop are threaded to receive nuts 13, preferably rectangular and arranged in a longitudinal slot or opening 14 of a turn buckle 15. The turn buckle is composed of spaced sides and connecting end portions 16, provided with smooth bores or openings 17 for the reception of the terminal portions of the binding rod or hoop. The inner faces of the sides of the turn buckle are parallel, and the nuts snugly fit within the slot or opening 14 and are adapted to be simultaneously rotated when the turn buckle is turned. The slot forms a guide or way for the nuts, which are slidably interlocked with the turn buckle. The ends 16 of the turn buckle are tapered and fit against the L-shaped plates at the inner ends of the enlargements of the attaching portions, and the turn buckle spaces the said plates and maintains a door opening of a permanent width.

The hoop or binding rod is yieldably maintained in engagement with the staves of the silo by means of a pair of coiled springs 18, arranged on the terminal portions of the hoop or binding rod and housed within the end portions of the longitudinal slot or opening 14 of the turn buckle and interposed between the nuts 13 and the ends 16 and adapted to be compressed by the said nuts. When the turn buckle is rotated, the coiled springs are simultaneously adjusted

to vary their tension and to produce the desired pressure on the staves of the silo. By this arrangement, a uniform tension is maintained on the ends of the binding rod 5 or hoop at each side of the door opening 3, and the turn buckle may be readily rotated by inserting a stick or similar implement in the central portion of the longitudinal slot or opening 14.

10 While only one binding rod or hoop is illustrated in the accompanying drawing, the rods or hoops of a silo will be arranged in the usual manner, and the adjusting devices for the same will be located sufficiently 15 close to form a ladder at the door opening.

What is claimed is:—

1. In combination with a silo having a door opening, a binding rod or hoop having threaded terminal portions projecting at the 20 door opening, plates secured to the exterior of the silo at opposite sides of the door opening and having portions extending into the same and arranged to engage the edges of the staves of the silo at the door opening, 25 said plates being also provided with horizontal openings through which the terminal portions of the binding rod or hoop pass, a turn buckle extending across the door opening and bearing against the said plates and 30 receiving the terminals of the said rod or hoop, nuts mounted on the threaded terminal portions of the binding rod or hoop, and coiled springs disposed on the latter and arranged to be compressed by the nuts..

35 2. In combination with a silo having a door opening, a binding rod or hoop having threaded terminal portions projecting at the said opening, approximately L-shaped plates consisting of exterior portions 40 secured to the outer faces of the staves of the silo at opposite sides of the door opening, and inwardly projecting flanges engaging the edges of the staves at the said

opening, said plates being provided with horizontally alined openings through which the binding rod or hoop passes, a turn buckle extending entirely across the door opening and fitting against the said plates and receiving the terminal portions of the binding rod or hoop, nuts slidably interlocked with the turn buckle and engaging the threaded portions of the binding rod or hoop, and opposite springs arranged to be simultaneously compressed by the nuts.

3. In combination with a silo having a door opening, a binding rod or hoop having threaded terminals projecting at the door opening, exterior plates secured to the silo at opposite sides of the opening and having inwardly extending portions engaging the edges of the staves at the said opening, said plates being also provided with openings through which the binding rod or hoop passes, and a turn buckle extending entirely across the door opening and fitting against the said plates and provided with a longitudinal opening and having smooth bores at the ends thereof through which the terminals of the binding rod or hoop pass, nuts engaging the threads of the terminal portions of the binding rod or hoop and slidably arranged in the longitudinal opening, and coiled springs disposed on the terminal portions of the binding rod or hoop and interposed between the nuts and the ends of the turn buckle and located within the opening of the latter and adapted to be simultaneously adjusted by the rotary movement of the turn buckle.

In testimony, that I claim the foregoing 80 as my own, I have hereto affixed my signature in the presence of two witnesses:

GEORGE HERMAN HORN.

Witnesses:

HARRY BOHMSACH,
ED FLANAGAN.
